ATTORNEY.

UNITED STATES PATENT OFFICE.

JOHN SABOLD, OF BOYERTOWN, PENNSYLVANIA.

DETACHABLE HANDLE FOR SAD-IRONS.

SPECIFICATION forming part of Letters Patent No. 379,416, dated March 13, 1888.

Application filed July 14, 1887. Serial No. 244,238. (No model.)

To all whom it may concern:

Be it known that I, JOHN SABOLD, a citizen of the United States, residing at Boyertown, in the county of Berks and State of Pennsylvania, have invented certain new and useful Improvements in Detachable Handles for Sad-Irons, of which the following is a specification.

My invention relates to that class of polishing or smoothing irons which have removable handles.

The object of my invention is to provide an improved device of this character adapted both for ordinary laundry sad-irons and tailors' irons.

15 In the drawings which illustrate the invention, Figure 1 is a side view of the sad-iron complete. Fig. 2 is a side view of the handle alone. Fig. 3 is a longitudinal vertical section of the iron-block, as shown on the line xx , Fig. 20 5. Fig. 4 is a cross-section of the iron and handle. Fig. 5 is a top view of the iron-block, and Fig. 6 is a bottom view of the handle.

The iron-block A may be of any desired shape or design. It has on top a recess, b, 25 which serves, before the top plate, C, is secured, for the insertion of a handle by which the block may be held while it is being polished or ground. The top plate, C, is secured on the iron block by rivets or screws c, or in any other 30 suitable way. This plate has a slot, d, which is reduced in width at its center by a flange, e, at two opposite sides. The greater breadth of the slot at each end d' is only sufficient to readily admit the two inclined lugs f on the bottom 35 of the handle. Each of the center flanges, e, is inclined on its under side, as at e', (see Fig. 3,) the thinnest part of the flange being adjacent to the broad end d' of the slot and from thence inclining to the thickest part. It will 40 be seen that in the present instance the thickest part of the center flange, e, is at its center—that is, midway between its two thin ends—and thus a reverse inclination is produced, affording an advantage hereinafter pointed out.

45 The top plate, C, is provided on its upper surface with two straight ribs, g, one at each long side of the slot d. These two ribs receive the base-plate of the handle between them and serve to give the handle steadiness when it is 50 in position on the iron. This top plate also has a downward rim-flange, h, which is provided with scallops, holes, or notches h' in the

edge which is in contact with the iron-block, to reduce to the minimum the metallic points of contact with the iron-block A, and thereby 55 prevent the conduction of heat from the said block to the top plate. The rim-flange h forms a recess or air-space, i, between the top plate and iron-block, and said air-space serves as a non-conductor and prevents the top plate from 60 becoming very hot.

The hand-grasp part J of the handle is made of wood or similar poor conductor of heat. A metal wire or rod, k, passes through the hand-grasp to each end upright, l, and a base-plate, 65 m, connects the two end uprights. The bottom surface, m', of the base-plate is flat and rests upon the upper surface of the top plate, C, between the two straight ribs g. This bottom surface is provided with a central longitudinal stem, n, having two laterally-projecting inclined lugs, f—one at each side—which will first enter one of the broad ends d' of the slot d in the top plate, and then take under the inclines e' of the flanges e, and thereby the 75 handle will be connected with the iron.

A lever, O, has a pivot, p, connecting it to the base-plate m, and at one end has a down-pointing prong, q, with an exterior segment-shaped face, q'. This prong projects down 80 through a slot, r, located in the base-plate back of the lugs f. It is important to notice that the curve of the segment-shaped face q' is eccentric with the pivot p. The other end of the lever O has on top a wooden knob, s, and below 85 has a spiral spring, t, which bears on the base-plate. This spring serves to keep the eccentric prong q in a depressed condition. By pressing down on the knob s the eccentric prong will be raised. When the handle is 90 placed in position, the lever-prong q drops into one end of the slot d, and the eccentric face q' of the prong impinges on the end edge, d' , (either end edge,) of said slot, and as the prong is pressed down the effect of the eccentric face 95 all the time impinging against the end edge, d' , will be to crowd or move the entire handle endwise, whereby the lugs f on the handle will be forced under the inclines e' of the top-plate flanges. Thus the lever carrying the eccentric face prong insures, first, that the handle will be tightly connected with the iron, and, second, it prevents the handle from accidental detachment.

It will now be understood that the lugs *f* and prong *q* of the handle may enter either end of the slot *d* in the top plate, and be secured under either end of the double or reverse inclines *e*.

5 In applying the detachable handle it is immaterial which end of the iron is foremost. Thus it will be seen that the inconvenience of turning the handle to adjust it to the iron is avoided, and the consequent trouble and delay 10 in fitting the handle to the iron-block is obviated, which is of evident advantage where rapid work is required.

Having described my invention, I claim and desire to secure by Letters Patent of the United 15 States—

1. In an improved sad or polishing iron, the combination of the iron having a top plate provided with a slot which has at two opposite sides a flange, *e*, inclined on the under side, a removable handle having a base-plate, *m*, provided on the bottom surface with two laterally-projecting inclined lugs, *f*, and a lever pivoted to the base-plate and having a downward-pointing prong, *q*, which is provided with a curved 25 face eccentric with the pivot, the said lugs *f*

and prong *q* being so arranged relatively that they will interlock with the base-plate when inserted from either direction, thus rendering the handle reversible, as shown and described, and for the purpose set forth.

2. The improved sad or polishing iron comprising the combination of the iron having a top plate provided with a slot which is broadest at each end *d'*, and at its center has side flanges, *e*, which are thinnest adjacent to the said broad ends, and from thence incline both ways to the center, where the flange is thickest, a removable handle having a base-plate, *m*, provided on the bottom surface with two laterally-projecting inclined lugs, *f*, to take 30 under the said inclined flanges, and means, substantially as described, to prevent the handle from accidental detachment.

In testimony whereof I affix my signature in the presence of two witnesses.

JOHN SABOLD.
